PULL FOR CABINET DOORS, DRAWERS AND THE LIKE

La Verne E. Clayton, Rockford, Ill., assignor to Amerock
Corporation, Rockford, Ill., a corporation of Illinois

Filed May 16, 1962, Ser. No. 70,156

Term of patent 14 years

(Cl. D10—8)

FIGURE 1 is a front elevational view of a pull for cabinet doors, drawers and the like showing my new design.

FIG. 2 is a side view.

FIG. 3 is a perspective view of the pull.

FIG. 4 is a top view.

FIG. 5 is a sectional view taken along the line 5—5 in FIG. 6.

FIG. 6 is a sectional view taken along the line 6—6 in FIG. 1.

I claim:

The ornamental design for a pull for cabinet doors, drawers and the like, substantially as shown.
